UNITED STATES PATENT OFFICE

ELMER G. GARTIN, OF CLAREMONT, NEW HAMPSHIRE, ASSIGNOR TO SULLIVAN
MACHINERY COMPANY, A CORPORATION OF MASSACHUSETTS

ROCK DRILL

Application filed October 1, 1929. Serial No. 396,559.

This invention relates to rock drills, and more particularly to improved pressure fluid operated feeding mechanism for a rock drill of the mounted drifter type.

An object of this invention is to provide an improved rock drill feeding mechanism. Another object is to provide an improved pressure fluid operated feeding mechanism for a rock drill of the mounted drifter type. A further object is to provide an improved rock drill feeding mechanism including a pressure fluid operated feeding motor of the cylinder and piston type and improved connections between the feeding motor and the drilling tool whereby a relatively long feed is obtained without materially increasing the over-all length of the drill. A further object is to provide in such a drill an improved pressure fluid operated feeding motor of the cylinder and piston type and improved rack and pinion mechanism between the feeding motor and the drilling tool whereby the rate of feeding movement of the feed motor is substantially multiplied. A further object is to provide a drifter type rock drill having a relatively long feed while an exceedingly compact structure is retained. Yet another object is to provide an improved pressure fluid operated feeding mechanism for use with a drifter type rock drill of a standard construction. These and other objects and advantages of this invention will, however, hereinafter more fully appear.

In the accompanying drawing there is shown for purposes of illustration one form which the invention may assume in practice.

In this drawing,—

Fig. 1 is a side elevational view of a drifter type rock drill having incorporated therein the illustrative form of the improved feeding mechanism, the feeding mechanism being shown partially in section to illustrate details of construction.

Fig. 2 is a transverse vertical sectional view taken substantially on line 2-2 of Fig. 1.

Fig. 3 is a transverse vertical sectional view taken substantially on line 3-3 of Fig. 1.

Fig. 4 is a detail sectional view taken on line 4-4 of Fig. 1.

Fig. 5 is a detail sectional view of the feed controlling valve mechanism shown in Fig. 1 with the valve shown in a different position.

In this illustrative construction there is shown a rock drill of the mounted drifter type including a drilling tool 1 having a usual hammer motor 2 which is adapted to percussively actuate a drill steel 3. As is usual in rock drills of the drifter type, the cylinder of the hammer motor 2 is provided with laterally projecting guide members or gibs 4 slidably mounted in parallel guideways 5 formed integral with a guide shell 6. This guide shell is provided with a usual swivel plate 7 which is adapted to be clamped in a suitable trunnion mounting of a tripod or column in a well known manner. In the present construction a feed cylinder 8 is formed integral with the guide shell and is provided with a longitudinal bore 9 in which a feed piston 10 is reciprocably mounted. The feed cylinder is provided with a front head 11 integral with the guide shell and a detachable rear head 12 suitably secured to the guide shell. As illustrated, the feed piston 10 is provided with a tubular feed piston rod 13 extending through an opening 14 in the front cylinder head 11 and having formed integral therewith depending ears or bosses 15 supporting a transverse bolt 16 as clearly shown in Fig. 4. Journaled on the bolt 16 is a spur pinion 17 meshing with the teeth of a stationary rack 18 formed integral with the guide shell and arranged in advance of the feed cylinder. Telescopically arranged within the tubular piston rod 13 is a slideable rod 19 having formed thereon rack teeth 20 also meshing with the teeth of the spur pinion 17. This rod 19 is secured by a nut and screw connection 21 to a clamp member 22 rigidly clamped to the front end of the drilling tool by means of a transverse clamping bolt 23. This rod is held against rotation relative to the clamp member 22 by means of a squared portion 24 thereon fitting a squared opening 25 in the clamp.

The improved fluid distribution means for the feed cylinder comprises a rotary throttle 100

valve 26 arranged in a transverse bore 27 formed in the rear cylinder head 12. This valve is provided with a usual operating handle 28. As shown in Fig. 1, communicating with the bore 27 are passages 29 and 30, the passage 30 communicating through a lateral port 31 with the cylinder bore at the front side of the feed piston, while the passage 29 communicates with the feed cylinder bore at the rear side of the piston. Traversing the wall of the throttle valve is a port 32 communicating with a fluid supply chamber 33 formed centrally within the valve. Also formed on the exterior periphery of the valve are circumferential grooves 34 and 35, while exhaust ports 36 and 37 connect the bore 27 to atmosphere. When the feed control valve 26 is in the position shown in Fig. 5, a pressure fluid is admitted from the supply chamber 33 in the valve through the port 32 and passage 29 to the rear end of the cylinder bore at the rear side of the feed piston. At the same time the pressure fluid within the front end of the cylinder bore is connected to exhaust through port 31, passage 30, groove 35 on the valve, and exhaust port 37. The pressure fluid acting on the rear pressure area of the feed piston 10 causes the latter to move forward within the cylinder bore and carry with it the gear 17 which meshes with the stationary rack 18 and the rack 20 on the rod 19. This gear reacting on the stationary rack rotates in a clockwise direction as viewed in Fig. 1 and as a result this gear, due to its meshing engagement with the rack 20, causes the rod 19 to be moved forward at a speed substantially twice that of the rate of movement of the feed piston. As a result the drilling tool 1 which is connected to the rod 19 by clamp member 22 is fed forward on the guideways on the guide shell, the rack and pinion construction between the feed piston and the drill causing the latter to be fed a distance substantially twice the distance of travel of the feed piston 10. When the drilling tool is fed to its extreme limit of forward movement relative to the guide shell, the feed control valve 26 is turned into the position shown in Fig. 1, thereby connecting the cylinder bore at the rear side of the piston to exhaust through passage 29, groove 34 in the valve, and exhaust port 36, while the cylinder bore at the front side of the feed piston is connected to the source of pressure fluid supply through port 31, passage 30 and port 32 communicating with the pressure chamber 33 in the valve. As a result the pressure fluid acting on the front pressure area of the feed piston causes the latter to move rearward, thereby feeding the drilling tool rearward in the guides on the guide shell to the position shown in Fig. 1.

As a result of this invention an improved pressure fluid operated feeding mechanism

is provided for a rock drill of the mounted drifter type wherein a relatively long feed is obtained without materially increasing the over-all length of the drill. It will further be noted that by the telescopic arrangement of the tubular feed piston rod and the sliding rack an extremely compact feeding mechanism is obtained. It will further be noted that an improved pressure fluid operated feeding mechanism is provided for a drifter type rock drill which is adapted to use with a rock drill of a standard design. These and other uses and advantages of this invention will be clearly apparent to those skilled in this art.

While there is specifically described in this application one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rock drill, a guide shell, a drilling tool guided thereon, pressure fluid operated mechanism for feeding said tool relative to said shell including relatively reciprocable cylinder and piston elements one of which has a chamber therein, connections between one of said feeding elements and the drilling tool including a rack secured to said shell, a pinion carried by and movable with one of said feeding elements and meshing with said rack, a second rack with which said pinion meshes and arranged to extend within said chamber in said feeding element, and a connection between one end of said last mentioned rack and the drilling tool.

2. In a rock drill, a guide shell, a drilling tool guided thereon, pressure fluid operated mechanism for feeding said tool relative to said shell including relatively reciprocable cylinder and piston elements one of which has a chamber therein, connections between one of said feeding elements and the drilling tool including a stationary rack secured to the guide shell, a pinion carried by and movable with one of said feeding elements and meshing with said rack, a sliding rack with which said pinion meshes and arranged to extend within said chamber, and a connection between the forward end of said sliding rack and the front end of the drilling tool.

3. In a rock drill, a guide shell, a drilling tool guided thereon, pressure fluid operated mechanism for feeding said tool relative to said guide shell including a stationary feed cylinder and a feed piston reciprocable therein and having a tubular piston rod, connections between said feed piston and the drilling tool including a pinion carried by and movable with said piston, a stationary rack secured to the guide shell, a sliding rack ar-

- ranged to extend within said tubular piston rod, said pinion meshing with said racks, and a connection for securing the forward end of said sliding rack to the front end of the drilling tool.
4. In a rock drill, a guide shell, a drilling tool guided thereon, pressure fluid operated mechanism for feeding said tool relative to said shell including relatively reciprocable feeding elements, and connections between one of said feeding elements and the tool including a sliding rack telescopically arranged within one of said feeding elements, a rack secured to the guide shell, and a pinion carried by and movable with one of said feeding elements and meshing with said racks.
5. In a rock drill, a guide shell, a drilling tool guided thereon, pressure fluid operated mechanism for feeding said tool relative to said shell including a stationary feed cylinder and a feed piston reciprocably mounted thereon, said feed piston having a tubular piston rod, and connections between said feed piston and the tool including a sliding rack telescopically arranged within said piston rod, a stationary rack secured to the guide shell, and a pinion carried by and movable with said piston and meshing with said racks.
6. In a rock drill, a guide shell, a drilling tool guided thereon, pressure fluid operated mechanism for feeding said tool relative to said shell including relatively reciprocable feeding elements, and connections between one of said elements and the drilling tool including cooperating toothed elements one of which is coaxially arranged with and telescopically arranged within one of said feeding elements and movable relative to said feeding elements during the feeding operation, and connections between one of said toothed elements and the drilling tool.
7. In a rock drill, a guide shell, a drilling tool guided thereon, pressure fluid operated mechanism for feeding the tool relative to said shell including relatively reciprocable feeding elements, and connections between one of said feeding elements and the tool including cooperating toothed elements one of which is telescopically arranged within one of said feeding elements, and connections between one of said toothed elements and the drilling tool.
8. In a rock drill, a guide shell, a drilling tool guided thereon, pressure fluid operated mechanism for feeding the tool relative to said shell including relatively reciprocable cylinder and piston elements, connections between one of said elements and said tool including a sliding rack arranged to extend within one of said elements, a stationary rack carried by the guide shell in advance of said feeding elements, and a pinion carried by and movable with one of said feeding elements and meshing with said racks, and a connec-
- tion between one end of the sliding rack and the drilling tool.
9. In a rock drill, a guide shell, a drilling tool guided thereon, pressure fluid operated mechanism for feeding said tool relative to said shell including relatively reciprocable cylinder and piston elements, and connections between one of said feeding elements and said tool including a sliding rack telescopically arranged with one of said feeding elements, a stationary rack secured to said guide shell, and a pinion carried by and movable with said reciprocable feeding element and meshing with said racks.
10. In a rock drill, a guide shell, a drilling tool guided thereon, pressure fluid operated mechanism for feeding the tool relative to said shell including a feed cylinder, a feed piston reciprocably mounted therein and having a hollow piston rod, and connections between said feed piston and the tool including a sliding rack telescopically arranged within said hollow piston rod and guided by the latter, said rack being slidable relative to said piston and cylinder, a stationary rack secured to said guide shell, and a pinion carried by and movable with said tubular piston rod and meshing with said racks.
11. In a rock drill, a guide shell, a drilling tool guided thereon, pressure fluid operated mechanism for feeding said tool relative to said shell including relatively reciprocable feeding elements one of which has a tubular portion, and connections between one of said feeding elements and said tool including cooperating relatively movable toothed elements one of which is telescopically arranged within said tubular portion, and connections between one of said toothed elements and the drilling tool.
12. In a rock drill, a guide shell, a drilling tool guided thereon, pressure fluid operated mechanism for feeding said tool relative to said shell including relatively reciprocable feeding elements one of which has a tubular portion, and connections between one of said feeding elements and the tool including a sliding element telescopically arranged within said tubular portion, a cooperating stationary element carried by the guide shell, and a rotatable element carried by and movable with one of said feeding elements and cooperating with said sliding and stationary elements.
13. In a rock drill, a guide shell, a drilling tool guided thereon, pressure fluid operated mechanism for feeding said tool relative to said shell including relatively reciprocable cylinder and piston elements, and connections between one of said elements and the drilling tool for transmitting motion to the latter including a stationary member, a member carried by and movable with one of said feeding elements and cooperating with said sta-

tionary element and rotatable through its cooperation with said element on movement of said last mentioned feeding element, and a member secured to the drilling tool and interengaging with said rotatable member, said member secured to the drilling tool being telescopically arranged within one of said feeding elements.

14. In a rock drill, a guide shell, a drilling tool guided thereon, pressure fluid operated mechanism for feeding said tool relative to said shell including relatively reciprocable cylinder and piston elements, and connections between said piston element and the drilling tool including a hollow piston rod, a member secured to said drilling tool and telescopically arranged with respect to said piston rod, a member carried by said piston rod outside said cylinder and interengaging with said telescopically arranged member and operative on rotation to effect longitudinal movement of the latter and of the drilling tool, and means for effecting rotation of said rotatable member including a stationary member extending longitudinally of said shell relative to which said rotatable member has movement on reciprocation of said feed piston.

15. In a rock drill, a guide shell, a drilling tool guided thereon, pressure fluid operated mechanism for feeding said tool relative to said shell including relatively reciprocable feeding elements, and connections between one of said elements and the drilling tool including cooperating toothed elements one of which has a longitudinal toothed portion coaxial with and telescopically arranged within one of said feeding elements, and connections between one of said toothed elements and the drilling tool.

In testimony whereof I affix my signature.
ELMER G. GARTIN.
